UNITED STATES PATENT OFFICE.

BOLLY A. JOHNSON, OF LOS ANGELES, CALIFORNIA.

LAWN SPRINKLER.

Application filed June 1, 1927. Serial No. 195,707.

This invention relates to water distribution, particularly to sprinkling devices, and has for its object the provision of a novel sprinkler head adapted for association with and used in connection with either a hose or a buried irrigating pipe, the construction of the head being such that when the parts are arranged in one position the water will be discharged in a circular spray.

10 In utilizing the ordinary type of sprinkler for lawns or gardens, such sprinklers throw the water on a path, sidewalk or roadway, this being disagreeable for the passersby, as well as wasting the water. With my invention 15 proved sprinkler, the proper sprinkler head may be chosen to throw the water to drop parallel to paths or sidewalks and to discharge water on a parkway parallel to a sidewalk and roadway.

20 Another important object of the invention is the provision of a sprinkler head which is adjustable so that the proper spray may be obtained in case of variation in the pressure of the water supply and so that 25 either a coarse or a fine spray may be obtained.

Another object is the provision of a sprinkler head of this character which is so constructed that when properly adjusted the flow of water therethrough will be cut off, the advantage of this being that in case a plurality of the sprinkler heads are used in connection with a buried irrigating pipe, any one or more of them may be cut out 35 without interfering in any way with the operation of the remaining ones.

Another object is the provision of a sprinkler head of this character which is so constructed that the water will rise higher 40 into the air before being converted into spray, this feature being important inasmuch as it tends to prevent the formation of a puddle in the immediate vicinity of the sprinkler head.

45 An additional object is the provision of a device of this character which will be extremely simple and inexpensive in manufacture, easily converted from one form for producing a circular spray into the other form for producing a strip spray, and to a third form if so desired, to produce a semi-circular spray, which will be highly efficient in use, durable in service and a general improvement in the art.

50 55 With these and many other objects in

view which will more readily appear as the nature of the invention is better understood, the same consists in the novel construction, combination and arrangement of parts, which will hereinafter be more fully described, illustrated, and claimed.

The essential features of the invention involved in the carrying out of the objects indicated are susceptible to modification; but a preferred embodiment of the invention is shown in the accompanying drawings, in which:

Figure 1 is a top plan view of the device showing the same in assembled relationship when a circular spray is desired. 70

Fig. 2 is a sectional view taken substantially along the lines 2—2 of Figure 1.

Fig. 3 is a sectional view taken substantially along the lines 3—3 of Figure 2.

Fig. 4 is a view similar to Figure 1, showing the parts in assembled relationship when a semi-circular spray is desired. 75

Fig. 5 is a sectional view taken substantially along the lines 5—5 of Figure 4, and

Fig. 6 is a sectional view of a still further arrangement of parts that are contemplated when a vertical strip spray is required. 80

The various figures described above adequately illustrate my invention, and the following detailed description is commensurate with the above mentioned drawings in enabling an artisan to construct and assemble the constituent parts of the same. 85

Referring more particularly to the drawings and especially to Figures 1, 2 and 3, 90 my sprinkling device comprises a body 10 preferably of cylindrical form having a hexagonal or other preferably angular shaped top portion 11. This body has a bore 12, the lower portion of which is threaded for engagement with the pipe section 13 shown in dotted lines in Figure 2, and the upper end of which is provided with a valve seat 14. When my sprinkler is installed, it is designed that the top of the 100 portion 11 be flush with the surface of the ground so that when the lawn is cut the sprinkler will not be in the way of a lawnmower or the like. A web 15 is provided within the body portion 10, which web has 105 a threaded aperture 16 extending therethrough.

Screwed within the upper portion of the bore 12 is a baffle member formed as of a conical disc 17 having a conical seat 18 on 110

the under side thereof. This baffle member is provided with a reduced shank 19 threaded as at 20 to be received within the threaded portion 16 of the web 15. This disc is provided with a head 21 having a screwdriver slot 22 therein and a nut 23 may be screwed on the lower end of the shank 19 to prevent unauthorized removal of the same by mischievous children or the like. An internal marginal flange 30 is provided above the web 15 for a purpose to be described hereinafter.

The operation of this form of the device is as follows:

Assuming that a circular spray is desired, the baffle member 17 is screwed into position in such a manner as to obtain the desired thickness of spray. If a thin spray is desired, the baffle member 17 may be closed upon the valve seat 14 to such a position as to obtain a narrow circular outlet for fluid; and if a thicker spray is desired, the baffle member 17 may be elevated from the valve seat 14. When water is turned on in the pipe 13, the same will pass around the web 16, pass the internal annular flange 30 and outwardly between the valve seat 14 and the surface 18 in the form of a conical spray. This form of the device is particularly useful for irrigating large areas of lawn, flowers, shrubbery and the like.

When it is desired to form a spray of semi-circular form, the device shown in Figures 4 and 5 is employed. The same body portion 10 is used, but the baffle member 17 is removed and a modified form of baffle member 17' is substituted therefor. This member comprises a tubular member 20' which is firmly pressed within the depression in the body portion 10 and rests against the flange 30 where it is held frictionally in position. The tubular member 20' is internally threaded as at 21' and a plug 22' having threads thereon is disposed within the tubular member. The plug 22' has a conical surface 23' and a conical valve seat 14' is formed within the tubular member. A slot 25' is cut within the side of the tubular member, and this slot may be cut either 180° around the tubular member, or more or less as may be desired. Adjustment of the plug 22' will secure the proper degree of thickness of the spray. This device is particularly useful when it is desired to irrigate lawns adjacent the side of a building or the like, and the spray may be directed outwardly from the building so that water may not be thrown against the building where it will trickle down the side of the same and form puddles adjacent the building. Furthermore, this type of spray will

insure full protection to the building by keeping the same dry so that the plaster of the same will not become damaged through sediment or rust that may lurk in the pipes. 65

The form shown in Figure 6 is adapted for use when a vertical spray is used as between sidewalks in a park or between buildings that are close together and the like. In this case, a small cup designated as at 70 17'' is frictionally inserted within the recess in the body member 10. This small cup 17'' has an outwardly extending annular flange 18'' and a slot 19'' is formed within the same so that water issuing from the pipe 13 will 75 pass around and through the spider 15 and through the slot 19'' where it will be projected upwardly, forwardly and rearwardly in the shape of a narrow web.

From the foregoing description and a 80 study of the drawings it will be apparent that I have thus provided a very simply constructed and consequently inexpensive sprinkler head which is convertible for use either in producing a circular spray or a 85 strip like spray, the device therefore having the great advantage of being capable of use under a wide variety of circumstances. Owing to the simplicity it is to be observed that there is practically nothing to get out of order and that the device should consequently have an extremely long life. 90

While I have shown and described the preferred embodiment of the invention, it is of course to be readily understood that I reserve the right to make such changes in the form, construction and arrangement of parts as will not depart from the spirit of the invention or the scope of the subjoined claim. 95

Having thus described my invention, what 100 I claim, is:

A sprinkler comprising in combination a body portion having a passage therethrough terminating in a cylindrical discharge opening, a web in said passage, a conical valve 105 seat flaring from said discharge opening, a baffle member comprising a conical head and a shank removably carried by said web and adjustable to position said head with respect to said seat, and an annular flange in said 110 passage between said discharge opening and web and cooperating with the wall of said discharge opening to form a seat for the reception, on removal of said conical head and shank, of any one of a plurality of variant 115 nozzles, each having its inlet end shaped to be frictionally received and retained in the discharge opening against the flange.

In testimony whereof I have signed my name to this specification.

ROLLY A. JOHNSON.
